CONTINUOUS WIRE DRAWING AND
ANNEALING

John R. McKean, Rumford, and Herbert S. Busey,
East Providence, R. I., assignors to Kennecott
Wire and Cable Company, a corporation of
Rhode Island

Application July 28, 1933, Serial No. 682,578

10 Claims. (Cl. 266—3)

Our present invention relates to the art of wire drawing, and has particular reference to an improved apparatus for annealing drawn wire.

It has heretofore been the practice, in wire drawing, to pass the wire through the drawing blocks to a spooling device, the filled spool then being conveyed to the annealing furnace for bright annealing of the wire, the practice thus necessitating an initial spooling followed by an annealing 10 and a final spooling. It is the principal object of our invention to devise an apparatus for the bright annealing of drawn wire which will not interrupt the manufacturing process and which is an integral part of the wire finishing operation.

15 The use of a separate annealing furnace has also increased the tendency to oxidation, and has increased the expense on account of the additional handling necessary. It is an additional object of our invention to provide an annealing furnace of small size, specifically adapted for annealing wire, the novel furnace including a simple arrangement for cooling the annealed wire before the wire contacts the atmosphere.

20 To this end, we have devised an annealing apparatus of small dimensions which may be detachably secured to existing wire drawing machines, and which is positioned between the wire drawing blocks and the spooling device, this apparatus continuously receiving the drawn wire as it leaves the blocks, annealing the drawn wire, and 25 cooling the drawn wire immediately after annealing and before it contacts the atmosphere so as to prevent oxidation, the annealed cooled wire then passing directly to the spooling device. The 30 cooling is preferably obtained by directing a stream of cooling water on the annealed wire, this cooling generating a curtain of steam to further exclude outside air.

35 Instead of utilizing external means for heating the annealing chamber, we have devised a novel arrangement utilizing a flame obtained by the combustion of a combustible material and an oxygen supplying material, such as illuminating gas and air, as the annealing medium, and have 40 provided an elongated annealing chamber to house the flame and to conserve the annealing heat. The flame may be readily regulated to properly anneal wires of different diameter, and the direct contact of the flame with the wire ensures a direct application of the annealing heat 45 and eliminates radiation losses.

To further reduce manufacturing expense, we 50 provide a control for the annealing gas and air that is dependent upon the operation of the wire drawing machine, thus eliminating all wastage of 55

fuel and air; burning and excessive heating of the wire when starting and stopping is also prevented.

An additional feature of novelty resides in the provision of safety means for preventing premature ignition and back fire, the preferred protection including a delayed flow for the air and a mixing construction which ensures a completely ignitable mixture of the flame ingredients and positively projects the flame into the annealing 10 chamber.

With the above objects and other advantageous features in view, our invention consists of a novel arrangement of parts more fully described in the detailed description following, in conjunction with 15 the accompanying drawings, and more specifically defined in the claims appended thereto.

In the drawings:

Fig. 1 is a side elevation, partly in section, showing the general arrangement of the continuous 20 wire drawing and annealing apparatus, and

Fig. 2 is a detailed section through the novel 25 annealing chamber.

Referring to the drawings, the wire drawing block 10 is of standard construction and in the embodiment shown is the finished wire drawing block; the wire W passes over the usual traversing guide pulley 11 to the spooling apparatus 12. An annealing apparatus 13 is positioned between the block 10 and the spooling apparatus 12, as 30 shown in Fig. 1, a suitable securing means including brackets 14 and 15 for receiving a bearing standard 16 on which the annealing apparatus 13 may be detachably secured.

The novel annealing apparatus includes an 35 annealing chamber 17 which is formed as an elongated tube, the rear portion being constructed as a burner 18 which is supplied with a combustible gas, such as illuminating gas, hydrogen, acetylene and the like through a valve 40 controlled gas inlet pipe 19 which conducts the gas to an annular chamber 20 communicating with a forwardly directed annular gas nozzle 21; air is supplied through an air inlet pipe 22 which 45 communicates with a circular air inlet chamber 23 terminating in a forwardly directed annular nozzle 24, the rear end of the burner having an opening 25 therethrough, preferably conical, for receiving the finished wire W from the block 10.

It will be noted that the wall 26 between the 50 nozzle is inclined, whereby the conical sheet of gas is projected into and through the conical sheet of air to thoroughly mix in the chamber 27, and is compressed by the inclined wall 28 to produce a smooth, completely burning jet or flame. 55

The forward direction of the gas and air nozzles thus ensure a uniformly combustible mixture in the annealing chamber, with no back fire, as the burner proper is completely filled with gas.

- 5 The gas and air burn to form an elongated flame of controlled length within the tubular chamber 17, to completely encircle the wire W and properly anneal the same, the chamber being preferably insulated to retain the annealing heat and to conserve the fuel supply. The direct contact of the flame with the heated wire from the drawing blocks eliminates radiation losses and thus further prevents heat loss.

The annealing chamber 17 projects into and is 15 slidably received in the upper portion of a cooling chamber 29, in which a grooved pulley 30 is rotatably mounted, the wire being wound around this pulley and exiting through an opening 31 in the form of an elongated slot in the front wall 20 of the cooling chamber to engage the traversing guide pulley 11. The pulley 30 is substantially submerged in water as shown in Fig. 1, the water outflowing through a valve controlled outflow 32 to waste and also passing through the opening 31 25 into an overflow chamber 33 which in turn communicates with the outflow 32. The sliding adjustment of the annealing chamber permits a control of the length of flame to properly anneal wire of different material and of different cross- 30 sectional area, which supplements and is in addition to control of the speed of wire travel.

A valve controlled cold fluid inlet 34 is mounted in the upper wall of the cooling chamber 29 and has a nozzle 35 positioned to direct a stream of 35 cooling fluid on the annealed wire at the point where the annealed wire passes out of the annealing flame, the cold fluid jet thus cooling the annealed wire, preventing contact of the atmosphere with the annealed wire, and serving to bring a constant supply of fresh cold fluid to the 40 cooling chamber. The impact of the cold fluid on the hot annealed wire generates vapor under slight pressure, which completely fills the cooling chamber and prevents entry therein of the atmospheric air. A splash plate or baffle 36 is preferably positioned adjacent the slot 31. The preferred fluid is water, but other cooling fluids adapted to reduce the temperature of the annealed wire below the oxidation temperature may 45 be used.

The control of gas and air to the burner 18 is 50 preferably subordinated to the wire drawing operation; the main line for the main motor controls 37 and 38 is therefore connected to a line leading to a solenoid coil 39 which operates the gas valve 40 through a lever system 41, and through an adjustable tension spring lever arrangement 42 operates the air valve 43, the lever system 41 having a manually adjustable weight 55 for regulating the action of the solenoid coil. It is thus seen that the gas supply is first opened, and the air supply is delayed, thus preventing formation of an explosive mixture in the burner. If desired, a mercury type delayed action solenoid 60 may be used for controlling the air valve.

The operation of the novel annealing arrangement may now be described; the wire W passes from the finishing drawing block 10 directly through the burner and through the flame in 65 the annealing chamber, which flame completely envelopes the wire and properly anneals it; just before the wire passes out from the annealing flame, it is cooled by the cooling jet of cold water, thus immediately reducing the wire temperature 70 below the oxidation point and ensuring a bright

finish, and is passed around the cooling pulley 30 to complete the cooling operation; the wire then passes over the traverse guide pulley 11 and is wound upon a spool in the spooling device 12.

It is thus evident that the wire passes continuously from the drawing blocks through the annealing arrangement and to the spooling reel, the wire being annealed in a neutral or a reducing flame and being cooled before it can contact with the atmosphere. It is further evident that the annealing furnace is simple in construction, is readily attached to existing wire drawing installations, is operated only when wire is being drawn, is inexpensive in use, and produces a high annealing temperature with a low fuel consumption. 15

Although the above description describes a specific structural embodiment of our invention, it is obvious that desired changes in the relative arrangement and proportions of the parts may be made, within the spirit and the scope of the 20 invention as defined in the appended claims.

We claim:

1. In combination, an annealing chamber, means for projecting a flame of combusting gases through said annealing chamber, and means for 25 conveying a wire to be annealed through said flame in the direction of the length of the flame.

2. In combination, an annealing chamber, a burner comprising spaced gas and air nozzles at one end thereof, and adapted to project an annealing flame into said chamber, and means for conveying a wire to be annealed through said flame in the direction of the length of the flame. 30

3. In an annealing furnace, a burner attachment having a longitudinal wire passage there- 35 through, a gas supply means, and an air supply means spaced therefrom, said supply means communicating with said longitudinal wire passage, whereby a flame produced by the combustion of the gas and air is projected in the direction of 40 the wire passage.

4. In combination, a cooling chamber, an annealing chamber communicating therewith and projecting therewith, means for drawing a wire through said annealing chamber and into said 45 cooling chamber, and means for impinging a jet of cooling fluid on said wire as it emerges from the annealing chamber.

5. In combination, a cooling chamber, an annealing chamber communicating therewith and projecting therewith, means for projecting an annealing flame through said annealing chamber, means for drawing a wire through said annealing flame and into said cooling chamber, and means for impinging a jet of cooling fluid on 55 said wire as it emerges from the annealing flame.

6. In combination, a cooling chamber having an opening, an annealing chamber of tubular formation extending through said opening, and means for projecting an annealing flame through 60 said annealing chamber and into said cooling chamber.

7. In combination, a cooling chamber having an opening, an annealing chamber for wire and of tubular formation extending through said opening, means for projecting an annealing flame through said annealing chamber and into said cooling chamber, and means for conveying wire through said annealing flame and into said cooling chamber. 65

8. In combination, a cooling chamber having an opening, an annealing chamber for wire and of tubular formation extending through said opening, means for projecting an annealing flame through said annealing chamber and into said 70 cooling chamber.

cooling chamber, means for conveying wire through said annealing flame and into said cooling chamber, and means for impinging said wire with cooling fluid in the region of its emergence from the flame and while the wire is above critical temperature.

9. In combination, a cooling chamber having an opening, an annealing chamber for wire and of tubular formation extending through said opening, means for projecting an annealing flame through said annealing chamber and into said cooling chamber, means for conveying wire through said annealing flame and into said cooling chamber, means for impinging said wire with cooling fluid in the region of its emergence from the flame and while the wire is above critical tem-

perature, and means for shifting the relative position of the flame and the cooling fluid.

10. In combination, a cooling chamber having an opening, an annealing chamber for wire and of tubular formation extending through said opening, means for projecting an annealing flame through said annealing chamber and into said cooling chamber, means for conveying wire through said annealing flame and into said cooling chamber, means for impinging said wire with cooling fluid in the region of its emergence from the flame and while the wire is above critical temperature, and means for shifting said annealing chamber to adjust the relative position of the flame and the cooling fluid.
